FORK OR SIMILAR ARTICLE OF FLATWARE

Milton Gonsiorek, Meriden, Conn., assignor to The International Silver Company, Meriden, Conn., a corporation of Connecticut

Filed June 22, 1965, Ser. No. 85,844

Term of patent 14 years

(Cl. D54—12)

FIG. 1 is a front elevational view of a fork showing my new design;

FIG. 2 is an enlarged front elevational view of the handle of the fork shown in FIG. 1, with the lower part broken away, depicting by the shading a pattern of composite and associated geometric angular indentations;

FIG. 3 is a rear elevational view;

FIG. 4 is a side elevational view;

FIG. 5 is a cross-sectional view taken to an enlarged scale and substantially on line 5—5 of FIG. 1; and

FIG. 6 is a cross-sectional view to an enlarged scale and taken substantially on line 6—6 of FIG. 1.

The design is intended for use on sets comprising forks, spoons, knives and similar articles of flatware.

I claim:

The ornamental design for a fork or similar article of flatware, substantially as shown and described.
